UNITED STATES PATENT OFFICE.

ROBERT D. GREGG AND FRANK L. SHIDLER, OF KANKAKEE, ILLINOIS.

CONCRETE PAVEMENT.

Application filed March 1, 1926. Serial No. 91,417.

This invention relates to that class of concrete pavements in which the mass of concrete forming the pavement is separated at proper intervals by parting strips of suitable material, usually a compressible asphalt and fibre strip. Such parting strips are positioned on the bed of the roadway before the filling in of the unset concrete mass is effected, with the strips remaining in place after the pavement is completed, and the present improvement has for its object:—

To provide a simple and efficient structural formation of a holding means, where-with parting strips of the nature above described are effectively held in place upon the roadbed, during the application of the concrete mass to form the pavement, and by which a liability of such parting strips to rise out of place during the making of the pavement is avoided, all as will hereinafter more fully appear.

In the accompanying drawings:

Fig. 1, is a detail longitudinal section, illustrating the preferred construction of the invention.

Fig. 2, is a perspective view of the holding and bracing member of the preferred construction.

Fig. 3, is a perspective view of a portion of the fibre board generally used to form parting strips.

Figs. 4 and 5, are detail perspective views of modified forms of the holding and bracing member.

Fig. 6, is a sectional elevation of another modified form of the invention.

Fig. 7, is a detail perspective view of the same attached to a section of the parting strip.

Like reference numerals indicate like parts in the several views.

The parting strips in general use in the laying, in sections, concrete pavements and the like, consists of thin slabs of compressible material, such as bituminous felt, having a height equal to that intended in the pavement, with the parting strips positioned on the road bed, to form one wall of the cavity that receives the mass of unset concrete which forms a section or unit of the pavement. As heretofore used parting strips of the type described were liable to vertical displacement during the formation of the pavement and form an objectionable protuberance on the top surface of the completed pavement.

With a view to an avoidance of the above mentioned difficulty this invention comprises broadly the fixed connection to the lower portion of a parting strip 1, one or more lateral anchor plates or extensions 2 adapted to rest upon the surface of the roadbed 4, and extending into the cavity, a wall of which is formed by the parting strip 1, and into which cavity the mass 3 of unset concrete is filled to form a section or unit of a concrete pavement of the present type. With the described arrangement of the anchor plates 2 an initial portion of the concrete filling 3 is placed in the portion adjacent to and upon the anchor plate, to more effectively hold the same down upon the roadbed against an accidental upward displacement of the anchor plate and of the parting strip 1 to which it is secured.

The fixed connection of the anchor plate 2 to the parting strip 1 may be attained by any usual connecting means, preferably by a fixed vertical flange 5 on said anchor plate 2, with such flange 5 provided with lateral prongs 6 adapted to be forced into the side of the parting strip 1 to attain the required fixed attachment between the parts, as illustrated in Figs. 1, 2, 4 and 5.

The scope of this part of the invention however, embraces a pivotal attachment of the anchor plate 2 to a side of the parting strip by a pivotal and pronged connecting link 7 as illustrated in Figs. 6 and 7.

In the preferred construction shown in Figs. 1, 2, 4, 6 and 7, the anchor plate 2 is formed with a flat portion 2' extending in an opposite direction to its main portion, with relation to the parting strip 1, and with a view to attain a proper initial vertical position of the parting strip 1, before the same is secured in position by the usual bracing board 9 and stakes 10.

Having thus fully described our invention, what we claim and desire to secure by Letters Patent, is:—

1. In a sectional concrete pavement, the combination of a parting strip, and an anchor plate arranged beneath the lower edge of the parting strip, and projecting into the cavity of which the parting strip forms a wall, the anchor plate having an integral vertical flange formed with lateral prongs for imbedment in a vertical side of the parting strip to attain fixed connection between the parts.

2. In a sectional concrete pavement, the

combination of a parting strip, and an anchor plate arranged beneath the lower ends of the parting strip and projecting into the cavity of which the parting strip forms a wall, the anchor plate having an integral vertical flange formed with lateral prongs for embedment in a vertical side of the parting strip to attain fixed connection between the parts, and with a flat portion extending in an opposite direction beyond the attached parting strip.

Signed at Kankakee, Illinois, this 24th day of February, 1926.

ROB'T D. GREGG.
FRANK L. SHIDLER.
